UNITED STATES PATENT OFFICE.

PATRICK TWOHIG, OF CLEVELAND, OHIO.

STEAM-ACCUMULATOR.

SPECIFICATION forming part of Letters Patent No. 338,237, dated March 16, 1886.

Application filed April 8, 1885. Serial No. 161,563. (No model.)

To all whom it may concern:

Be it known that I, PATRICK TWOHIG, a citizen of the United States, residing at Cleveland, county of Cuyahoga, and State of Ohio, 5 have invented certain new and useful Improvements in Steam-Accumulators; and I do hereby declare the following to be a description of the same, and of the manner of constructing and using the invention, in such full, clear, concise, and exact terms as to enable any person skilled in the art to which it appertains to construct and use the same, reference being had to the accompanying drawings, forming a part of this specification, the 15 principle of the invention being herein explained and the best mode in which I have contemplated applying that principle, so as to distinguish it from other inventions.

The drawing represents a side elevation of 20 the invention, partly in section.

A is the accumulator.

B is a pipe leading from a power-transmitting engine and emptying exhaust-steam into the accumulator. Said pipe is provided with 25 stop-cock b.

C is a pipe leading from a pumping-engine, and also empties exhaust-steam into the accumulator. Said pipe is provided with stop-cock c.

30 In the top of the accumulator are inserted the two steam-heat pipes D, connected with the steam-radiators, and respectively provided with stop-cocks d. Said pipes D extend downward a considerable distance into the accumulator, the object of which is hereinafter explained. A pipe, E, passes into the accumulator at any convenient point in the top and extends downward to a point, e, below the horizontal line of the discharge- 35 40 mouths of the pipes B C, and is designed for the escape of surplus steam. Said pipe E is provided at a point external to the accumulator with the back-pressure valve e', by which surplus steam escapes into the open air. Said valve, being loaded, acts as a safety-valve.

F is an aperture through the bottom of the accumulator, through which the water condensed from the steam discharges into the 50 basin G. Said basin is connected by a pipe, H, with the surface-trap I.

J is a conical cover placed over aperture F and raised slightly from the bottom of the accumulator on the lugs f, thus providing a space, f', between the bottom of said cover and the aperture.

K is a steam-gage by which the pressure of steam in the accumulator is shown.

To obviate pulsations of steam in the accumulator is the design of the extension of 60 the heat-pipes D, whereby steam packs about the depending ends d' of said pipes, said packed steam acting as an elastic cushion to break said pulsations, thereby securing constancy of pressure through pipes D.

Pipe E is made to depend so far as is described toward the bottom of the accumulator in order that the pressure needed to force the steam through pipes D may not be too soon interfered with by the operation of the said 70 surplus-steam escape-pipe.

Although, as stated, the primary object of my invention is to use exhaust-steam for heating purposes, yet it may be also used as a convenient and successful water-catcher; also, 75 if no accumulation of steam for heating purposes is desired, the accumulator, in connection with the discharge-pipe E, affords a convenient medium of conveying exhaust-steam into the open air, in which case the back- 80 pressure valve is unloaded. The cover J acts as a breaker to the pulsations of the ingushing steam, so that the water in basin G is kept from splashing.

What, therefore, I claim is—

1. The combination, with a steam-accumulator provided with one or more inlet-pipes and one or more outlet-pipes, the latter depending within the accumulator, of a surplus-steam discharge-pipe depending within the 90 accumulator and having its receiving-mouth on a horizontal plane below the horizontal plane of the mouth or mouths of said inlet pipe or pipes, substantially as set forth.

2. The combination, with a steam-accumulator provided with one or more steam-inlet pipes and also provided with one or more steam-discharge pipes located at the top of the accumulator, of an independent surplus-steam escape-pipe depending within the accumulator and having its open receiving end located below the mouths of said steam-dis-

charge pipes and also below the discharging end of said steam inlet pipe or pipes, substantially as set forth.

3. The combination, with steam-accumulator A, provided with one or more supply-pipes and one or more discharge-pipes, the latter having their receiving-mouths depending below the accumulator-top and above the horizontal plane of the discharge-mouths of the supply-pipes, of the surplus-steam escape-pipe E, depending within the accumulator and having its open end located below the mouth of said supply-pipes and nearer the bottom of the accumulator, substantially as set forth.
- 15 4. The combination, with a steam-accumulator, of a water-basin located at the bottom of the accumulator, and a cover located over the basin and forming horizontal water-pas-

sage f' between the same, said steam-accumulator provided with one or more steam-supply 20 pipes connected therewith in a horizontal plane above said basin-cover, substantially as set forth.

5. The combination, with a steam-accumulator provided with a steam-supply pipe, of a 25 water-basin depending below the accumulator-bottom and a conical cover located slightly above the latter, substantially as set forth.

In testimony that I claim the foregoing to be my invention I have hereunto set my hand 30 this 4th day of April, A. D. 1885.

PATRICK TWOHIG.
